UNITED STATES PATENT OFFICE.

FRANKLIN L. CHAMBERLIN, OF CLEVELAND, OHIO.

CARTRIDGE-LOADING MACHINE.

SPECIFICATION forming part of Letters Patent No. 295,980, dated April 1, 1884.

Application filed April 17, 1883. (No model.)

To all whom it may concern:

Be it known that I, FRANKLIN L. CHAMBERLIN, of Cleveland, in the county of Cuyahoga, and State of Ohio, have invented certain new and useful Improvements in Cartridge-Filling Machines; and I do hereby declare the following to be a full, clear, and exact description of the invention, such as will enable others skilled in the art to which it appertains to make and use the same.

My invention relates to improvements in a machine for filling cartridge-shells, and more especially for filling shells that are used in shot-guns; and it consists in certain features of construction and in combination of parts hereinafter described, and pointed out in the claims.

In the drawings, Figure 1 is a front elevation of my machine. Fig. 2 is a plan view of the bottom of an intermittently-revolving disk, showing notches by which the disk is actuated, and showing, also, the holes in which a dog or pin operates to hold the disk in accurate position when the disk is at rest. The top portion of Fig. 3 represents in vertical section a portion of the disk shown in Fig. 2. The lower portion of the figure represents a shaft and a revolving arm that actuates the disk, while the middle portion represents in section a portion of the table of the machine.

Fig. 4 represents in section a portion of the disk and table, and shows, also, the pin or dog for holding the disk accurately in place. Fig. 5 is a plan view of the top of the disk that is shown in Fig. 2, and shows, also, a portion of the table, levers, gearing, and other attachments of the machine. Fig. 6 is a plan view of the bottom of an arm with certain portions of the wad-pushing device attached. Figs. 7 and 8 are plan views, showing different positions of a lever that actuates the wad-pushing device.

Fig. 9 is a plan view of a lever and dog that hold a cartridge from revolving while it is being crimped. Fig. 10 is a plan view of a spider, the arms of which support various portions of the machine, also are seen portions of the device for placing the wads, and also the gates or valves for measuring and discharging the powder and shot. Fig. 11 is a vertical sectional view of one of the arms of the spider shown in Fig. 10, but showing, also, the wad-pusher, wad-starter, the wad-fingers, and a

portion of the wad-holder. Fig. 12 is an elevation, partly in section, showing a gate or valve and a segment-gear and rack for operating the same, and showing, also, a cartridge-shell and a crooked lever by the joint action of which the segment-gear and rack are engaged or separated, as is required. Fig. 13 is a plan view of a cross-head with its various arms, and showing in section a supporting and guiding shaft or column and inclosed bolt. Fig. 14 is a vertical sectional view of the said supporting shaft or column, with an internal bolt and other devices for supporting and adjusting the spider shown in Fig. 10, a portion 65 of said spider being also shown in Fig. 14. Fig. 15 is a vertical sectional view of a wad-rammer. Fig. 16 is a vertical sectional view of a marker. Figs. 17 and 18 are views of a crimpler, one in elevation and one in section. 70 Fig. 19 is a view in perspective of a receptacle for cartridge cases or shells, a cut-off device, and a guiding-tube, and in section a slotted rod that actuates the cut-off device. Fig. 20 is a vertical sectional view of a punch and 75 a cartridge-shell, the parts being in position for removing a cap or primer that is also shown. Fig. 21 is a vertical sectional view of a cartridge-shell and the device for capping or priming shells. Fig. 22 is a vertical sectional 80 view of portion of the mechanism for crimping or closing the cartridge-shell above the wad. Fig. 23 is a cross-section of the tube containing the caps or primers with a primer inclosed. Fig. 24 is a horizontal section of 85 the cartridge and the shot-filling tube, and showing the bent lever for holding the filling-tube in position relative to the cartridge.

A represents a vertical central shaft firmly supporting the table a , and terminating in a 90 broad flange or base, A' , that supports the machine.

Under the table, and supported therefrom by the pendent boxes a' , is the cross-shaft B , to the ends of which are firmly attached the 95 spur-gears B' , that are driven from the crank-shaft B^2 by means of pinions B^3 . The gears B' are also crank-wheels, and are provided with the wrists b , to which are attached the pitmen b' , that operate the cross-head C . (See 100 also Fig. 13.) The shaft A acts as a guide for the cross-head, and is provided with a groove,

in which operates the feather c , that is attached to the cross-head. The cross-head is also provided with the arms c' , both of which terminate alike in thimble ends, that are threaded 5 on their inner surfaces for the adjustment and support of the rammers C , that, by means of their screw ends, are supported therefrom. These rammers force the wads into the cartridge-shells, as will be hereinafter described, 10 and are each made self-adjusting by means of a slip-joint and a coil-spring, F , operating between the shoulder of the screw end above and the shoulder of the rammer below, (see Fig. 15,) and held in place by the cross-pin f , operating 15 in a slot in the inner part of the rammer and attached firmly to the outer part, the arrangement of parts being such that by the compression of the spring any excess of pressure on the end of the rammer will be relieved.

20 In the orifice c^2 , that is located in one arm of the cross-head, operates the crimper C^2 , that crimps or closes the top of the cartridge-case over the top wad, to prevent the wad from moving. (See Figs. 17 and 18.) By means 25 of a quick thread in the orifice c^2 , engaging a corresponding thread on the top portion of the crimper, rotary motion, but alternately in opposite directions, is given to the said crimper by means of the reciprocating motion of 30 the cross-head. This crimper passes through and is guided by the stationary thimble E^2 , and is provided just above this thimble with a slip-joint, as shown in Figs. 17 and 18, in which the lower part of the crimper engages 35 a socket in the upper part, forming a slip-joint. The outer and upper part of the socket is provided with jam-nuts R , and the lower and inner part with a pin, R' , that is firmly attached to the said inner part and operates 40 in a slot made in the outer part, the said pin supporting a collar, R^2 . Around this part of the crimper is a coiled spring confined between the said jam-nuts and the said collar, and the arrangement of parts is such that by means 45 of the compression of the said spring the slip-joint operates so as to relieve the crimper of any excess of pressure on the end of the same; also, by means of these jam-nuts R the tension of the said spring can be so adjusted as 50 to cause the said crimper to operate with the required maximum of pressure.

Below the thimble E^2 , and attached to it, is the coiled spring r , that acts in the double capacity of a spring and a nut. The crimper 55 at this part is provided at r' , with one or two threads of a screw, commonly called a "worm," that engages the coil-spring r . When a rotary motion is given to the crimper by means of the downward motion of the cross-head, the 60 crimper will, by the said engagement of the said worm r' with the coil-spring r , be advanced downward just as an ordinary bolt under such circumstances would be turned down through its nut; but if the end of the (supposed) bolt 65 should meet obstruction it would lift on its nut, and if this nut were held down by a

spring it would compress the spring. So the crimper, when it comes in contact with the cartridge-shell and can go down no farther, lifts its nut, which is that part of the spring 70 r that happens to be in contact with said worm r' , and compresses that part of the spring that is above the worm r' . Of course the amount of compression of this spring is the measure of pressure in the contact of the 75 crimper with the shell. If, by reason of a longer shell or from any other cause, the pressure might become too great, the slip-joint and spring that is above the thimble E^2 , and hereinbefore described, will relieve the parts, as 80 aforesaid. Of course an upward motion of the cross-head will reverse the rotary motion of the crimper and cause it to advance upward. The lower end of the crimper is recessed in the proper shape for crimping the 85 shell, as shown in Fig. 18, and this recessed end is made detachable from the spindle.

When it is desired to load shells with charges so small that the top wad is pressed some distance below the top end of the shell, it is not 90 practicable to crimp the upper edge of the shell down so far as to hold the wad firm. In such case it is better to hold the wad in its place by creasing the sides of the shell by means of grooving or creasing just at the top 95 edge of the wad. My device for this purpose is shown in Fig. 22, and is attached to the spindle of the crimper, and is interchangeable with the recessed end aforesaid. (Shown in Figs. 17 and 18.) The device consists of a 100 central cylindrical piece of metal or plug, S , with the lower end flat and adapted to press down on the wad during the creasing process. The top end is made suitable for engaging the lower end of the spindle of the crimper aforesaid, while the middle portion is provided with a transverse mortise, into which are pivoted the bent arms S' , to the lower end of which are attached the rollers S'' , of suitable shape for creasing the sides of the shell, as aforesaid. These 105 arms are drawn toward each other by means of a coil-spring attached from one arm to the other, and the arms are forced apart against the tension of the spring by means of a toggle-joint attached to the arms, as shown in Fig. 22. 110 These arms are drawn toward each other by means of a coil-spring attached from one arm to the other, and the arms are forced apart against the tension of the spring by means of a toggle-joint attached to the arms, as shown in Fig. 22. 115 The toggle-joint is operated in one direction by means of a small rod, s , attached thereto, and so arranged that when the said arms are distended by means of the arms of the toggle-joint being in line the lower end of the said 120 rod will extend below the central plug, S , and thereby first come in contact with the wad, by means of which the toggle-joint will be forced out of line or deflected upward, thus allowing the arms to be drawn toward each other by the spring S' aforesaid, and thereby causing the said rollers to be pressed against the sides of the shell, which, by means also of the rotary motion of the parts, creases or grooves the shell at the top edge of the wad as desired. Attached to the said toggle-joint, and leading a 125 short distance upward, is a small rod, s' , with

the upper end thereof suitable for pressing against the ring s^3 while the said rod is revolving around the axis of the said crimper's spindle. The ring is provided with a slide, s^3 , that is embraced and guided by the thimble E^3 and that extends upward so as to encounter the cross-head near the end of its downward stroke and be pressed down thereby, and by means of the aforesaid engagement and attachments 5 to pressing downward into a straight line, the said toggle joint thereby distending the arms, so that in the upward motion of the crimper that immediately follows, the rollers on the ends of the arms will not encounter the shell of the cartridge. The arms S will then continue distended until by an engagement on the downward stroke with another cartridge the creasing operation will be again repeated.

From an arm, c^3 , of the cross-head C^3 is suspended and operated the marker C^3 for marking the top wad of the cartridges. (See Fig. 16.) To the extreme end of the arm c^3 is attached the slotted rod N^3 , operating the arm N^3 of a rock-shaft and cut-off device N^3 , that are 20 attached to and operate in connection with the inclined container-box O , in which the cartridge-shells are placed preparatory to being fed into the machine. The cut-off device is attached to the said rock-arm, and is in the 25 shape of an inverted trough, and located so near the bottom of the container that a shell cannot pass between the two, except as the cut-off is rocked or oscillated. When, near the end of the upstroke of the cross-head, the 30 slotted rod N^3 engages the arm N^3 and raises the upper edge of the said trough, a shell will by its own gravity roll under the said trough. When, by the downward stroke of the cross-head, the top edge of the trough is lowered 35 and the lower edge raised, the shell will pass out from under the trough or cut-off, and, coming in contact at its outer end with the transversely-inclined end of the container, the shell is discharged 40 otherwise into one of the holders hereinafter described.

To insure the proper entering of the shell into the holder, there is provided the vertical guiding-tube O' , the inner half of which, O^3 , is a door that is hinged to the outer half, and is 45 closed by the arm N^3 , attached to the said rock-shaft and operating on a pin on the door. This closing of the door of the guiding-tube occurs just as the shell is discharged from the container-box into the machine. Directly afterward the arm N^3 is withdrawn, and the said door is opened by means of a spring attached 50 to hinges of the said door. The opening of the door allows the shells to be carried away by the holders, as will be hereinafter described.

60 To the cross-head also are attached the racks h , the punch P , and the capping device P' , all hereinafter described.

D represents a disk that has its bearing and axis on the shaft A , just above the table a , and 65 revolves with an intermittent motion that is provided by the arm b^3 , attached to the shaft

B, that once in a revolution of the said shaft engages one of an annular series of notches on the bottom of said disk, and causes the disk to turn the required distance, a slot in the table a allowing the said arm to revolve and operate as aforesaid. During the stops, or times that the disk remains at rest, the disk is kept firm in its place by means of the pin a^2 , that extends through the table a , and engages one of an annular series of holes in the bottom of the disk, and is held to this engagement by means of a spring, a^3 . This pin is tripped out of its engagement with the disk by the cam b^4 , that is also attached to the shaft B , and is arranged in such manner as to operate to withdraw the pin a^2 from the disk D when the arm b^3 is acting upon said disk.

The bottom view of the disk, Fig. 2, shows the notches and holes in which the arm b^3 and the pin a^2 operate, as aforesaid. At the periphery of the disk, and with equal spaces intervening between them, are attached the holders d , that receive the empty shells as they are delivered into the machine, as aforesaid, and carry them by means of the aforesaid intermittent motion of the disk from station to station, to receive the different parts of the loading and other treatment incident thereto. These holders are divided vertically in halves, 95 and the inner halves are firmly attached to the disk, while the outer halves are hinged to their respective inner halves like doors, but with springs attached in such a manner to their respective hinges as to press the two parts 100 of the holders together. (See Fig. 1.) Pendant from the bottom edge of the forward corner of the doors of the holders are the pins d' . (Shown in Fig. 2.) By the engagement of these pins with the incline a' , that is attached 105 to the upper side of the table a , the doors of the holders are opened at the proper time to discharge from the machine cartridges that have been loaded and finished, and are held open by this engagement until the holder has 110 received an empty shell in place of the loaded one just discharged. Immediately after this, and by the disengagement of the said pin with the said incline, the said holder closes around the shell, holding it firm in its place during its 115 rotation with the disk.

Pivoted to the table a , Fig. 5, are the vertical spindles G , to which are attached the levers G' . These levers are placed so close to the table that holders pass over them without contact. The metallic end of the shell, however, extends below the holder, and as it is passed in its proper holder, as aforesaid, it engages and actuates the said levers, first forcing back the toe of the lever as the shell approaches the station in front of which the lever is fulcrumed. As the shell leaves the station it comes in contact with the heel of the lever and reverses it or throws it back into its first position. (See Figs. 7 and 8.) These 125 movements of the spindle G , produced by the cartridges in the holders, serve to actuate the

wad-pushers hereinafter described. Fully crumpled to the table a , and shown also in Fig. 5, is the lever G^3 , provided with teeth on one edge for engaging the metal end of shells at the crimping-station. (See Fig. 9.) On the opposite side of the shell is a small stationary dog, G^4 , with one or more teeth that engage and support the shell as against the pressure of the lever. The combined action of the dog and lever holds the shell from revolving during the crimping process. The pressure of the lever G^3 against the shell is caused by the pressure of the rim of the contiguous wheel B against the lever. By means of a recess in the rim of the wheel B , that comes opposite the lever just as the crimping process is completed, and by the action of the shell, the lever G^3 is drawn back into said recess, and remains back while the crimped shell is carried forward and another shell is brought to the station to be crimped.

E represents a spider adjustably attached to the shaft A a short distance above the disk D . The upper part of the shaft A is hollow, as shown in Fig. 14, and incloses a bolt, A^2 , that is attached to the hub of the spider E by a pin, A^3 , that operates in a slot in the shaft A . The bolt A^2 is provided with the nut A^4 , that rests on the end of the shaft and terminates in a boss that extends into a recess in the end of the said shaft. A small set-screw extends through this part of the shaft, and engages a groove in the said boss, and prevents the nut from lifting. By means of the said pin, bolt, and nut, the spider may be raised or lowered, and thereby accurately adjusted. To the arms of this spider are attached several parts of the machine, to wit: To the arm E' is attached the powder-container, and the arm E'' supports the shot-container. One arm terminates in the thimble E' , connected with the crimper already described. To the arms E are attached the wad-holders, the wad-pushers, and their respective attachments. The wad-holders K are vertical, and are attached only to the sides of their respective arms, and may be made of tubes, but preferably of rods arranged in a tubular form, as shown in the drawings, which construction admits of thrusting a quantity of wads held between the thumb and finger into the wad-holder between the rods from above, the elasticity of the rods rendering them self-adjusting. (As the wads are received in packages, from which they may readily be lifted in quantities between the thumb and finger, the convenience of this kind of wad-holders is made apparent.) The wad-holders are provided at the top and at the bottom with thimbles, to which the rods are attached for mutual support. The lower thimble, k , is placed far enough above the arm E to admit of wads of any desired thickness passing between the arm and the thimble. On the outside of this thimble operates a second thimble, k' , that may be so adjusted as to more or less close the aforesaid opening between the arm and the inner

thimble, k , and gage it to about the thickness of the wads used, so that but one wad can be pushed out at the same time. Outside of the wad-holders, but operating on and embracing the same arms E , respectively, are the slides l , projections of which, l' , extending toward the wad-holders, constitute the wad-pushers, and are adapted to push the bottom wads out from under the columns of wads in the wad-holders when the slides l are advanced for that purpose. The slides are operated from below by means of the slotted levers g , that engage the pins g' , attached rigidly by means of the arms g'' to their respective slides l . These slotted levers g are firmly attached to the spindles G , that are actuated by the levers G' , as aforesaid, so that when shells approach wad-station by means of their actuating the levers G' , as aforesaid, wads are thrust from the wad-holders to the fingers e , respectively, where they are held in position over the thimble e' , to be forced at a proper time by descending rammers into shells beneath. The thimble e' has a lining-tube, e'' , or wad-starter, resting on a coil-spring, e''' , that in turn rests on the outer casing of the thimble. (See Fig. 11.) As the rammer C forces the wad from the grasp of the said fingers and through the starter e'' , the friction between the said wad and starter is such as to force the starter down in contact with the end of the shell e^4 , that is just underneath it, making a continuous passage-way for the wad, that insures its entering the shell in a proper manner. When the wad leaves the starter and enters the shell, the starter, by means of the spring e''' aforesaid, is raised to its former position contiguous to the fingers aforesaid. The fingers (see Fig. 10) are forced apart slightly by the wad as it is thrust between them by the wad-pusher, and by means of a spring, e^4 , acting expansively, the fingers are made to grasp the wad sufficiently firm to hold it suspended over the wad-starter until the descending rammer forces the wad to the cartridge-shell, as aforesaid. The containers for powder and shot are upright vessels, that terminate below in discharging-tubes that are provided with gates or valves, by means of which the powder and shot are measured and discharged at times and in quantities as desired. These valves are of a variety that consists of a horizontal cylindrical chamber cutting transversely the discharging-tube, and in which operates a hollow plug, h , that has a broad slot, h^3 , or opening on one side of it. When this slot is turned up, the powder or shot from the container above will fill the cavity in the plug. When the plug is turned so that the slot is below, the contents of the plug will be discharged through the pipe below into the cartridge-shell. To these plugs or valves are attached the segment-gears h' , that are operated by the racks h , attached to the cross-head, as aforesaid. The adjustment of the parts is such that the upward movement of the cross-head turns the plug

or valve in the position to be filled from the container above. The downward stroke of the cross-head gives a half-revolution to the plug, which brings it in position to discharge its contents below. A lever, h^6 , is attached by means of the collar h^7 to the discharging-tube, and adjusted in such a manner that when shells e^8 approach the stations they engage the said lever, and by means of this engagement 10 turn the guiding-tube in its bearing on the arm of the spider, and turn with it, also, its attachments—such as the segment-gear h^9 —and changes the gear from the position shown in the upper dotted lines, Fig. 24, to the lower dotted lines, in which last position (shown also in Fig. 12) the gear engages the rack h^10 , and is actuated thereby, causing the powder or shot to be discharged into the shell. When the shell leaves the station, it engages another part 20 of the lever, by means of which the parts are turned in the opposite direction, bringing the segment-gear into the position shown by the upper dotted lines, Fig. 24, in which position it does not engage the said rack. If for any 25 reason a shell were not in position in the holder to engage the lever h^6 , the segment-gear h^9 would remain inoperative and no ammunition would be discharged. The size and arrangement of the respective slots in the plug and 30 in the wall of the casing are relatively such that the receiving passage-way into the plug will be closed before the discharging passage-way will have commenced to open.

In operating the valve attached to the shot-35 container, it was found that sometimes, in closing the valve above, shot would be caught between the edge of the valve at the slot h^3 and the edge of the casing, whereby either the valve would be stopped from turning or the 40 shot would be mutilated. To obviate this difficulty, I have devised a secondary-chamber, h^4 , opening into the primary-chamber or valve-seat, the said opening between the two chambers taking the place of the aforesaid objectionable shearing-edge of the casing, and in 45 place thereof this part is made elastic, preferably by filling the secondary-chamber with rubber h^5 . The operation of this part of the device is such that when shot are caught, as 50 aforesaid, they are pressed back into the yielding contents of the secondary-chamber, and by the elasticity of the same the shot are ejected from this secondary-chamber as soon as, by the opening of the valve, the pressure is removed 55 from this part. Usually the cartridge shells or cases that are filled on this machine are new, and are provided with primers that were attached when the shells were manufactured. Sometimes, however, it is desired to fill shells 60 that have before been used, and consequently the primers have been exploded. It is necessary, in order to use these shells again, to remove the exploded caps and to replace them with new ones.

65 For removing the old caps, we have the punch P , attached to and operated by the arm

p of the cross-head, and operating directly over one of the stations where the shell stops. Directly under the point of the punch is a hole, p^1 , in the table a , of suitable size, so that 70 when the punch descends, the point thereof, coming in contact with the cap, forces it from its contact with the shell through the hole p^1 , causing it to be discharged from the machine. (See Fig. 20.) To the arm p' of the spider E 75 is attached the set P' , that is a part of the capping device. The caps are placed in a proper manner in the tube p^2 , that is adapted to receive the caps and convey them to the anvil p^3 , that is set just below the surface of 80 the table in the recess T . The capping-tube is hinged at t and supported by springs t' , as shown. This part of the device is so far depressed below the surface of the table a that the shells carried by the disk D will 85 pass above it, and so located that when the shell stops at this station the hole in the bottom of the shell, from which the old cap has just been punched, will be directly over the cap that is on the anvil p^3 . When the set P' 90 descends, the shell is forced down in contact with the cap that is on the anvil, and by means of said set the cap is forced home to its place in its shell, the capping-tube receding down upon its springs as the shell descends, 95 and, by means of the said springs, immediately regaining its first position when the pressure of the shell and set have been removed. To the left of the capping-tube is shown a section of the tube with a cap inclosed. 100 (See p^2 , Fig. 23.)

To the upper end of the shaft A is attached a rod, supporting the disk M , and still above supporting the bell M' . To the disk are attached the bell-hammers r . These hammers 105 are pivoted in the central part, and so arranged that a downward pressure on the outer end will cause the hammer end to strike the bell M' . These hammers are so arranged on the disk M that the outer ends are contiguous to 110 the rods f' , attached, respectively, to the rammers C' , Figs. 1 and 15. These rods are pivoted with adjustable collars, that, when the machine is working properly, come at the lower end of their stroke very near, but do 115 not touch, the said bell-hammers. It will be seen, Fig. 15, that these rods do not connect with the screw-end part of the rammers, but connect with the part that extends below and forms the rammer end of the device. These 120 rammers, when they have forced the wads firmly upon the powder or shot, can go down no farther, and remain stationary, while, by means of the slip-joints aforesaid, the cross-head can still descend to the end of its stroke. 125 In case there were no powder or shot below the wads, the rammers would not meet with such resistance as would stop their advance downward; but the rammers would in that case continue down with the cross-head to the end 130 of the stroke. This would bring the said collars on the rods f' down on the bell-hammers.

and sound an alarm, that would show that something was wrong and that there was short ammunition in the cartridge-shells.

The general operation of the machine, of which I have already given the description in detail, is as follows: Powder, shot, wads, and cartridge-shells having been supplied in a proper manner to the respective containers, holders, and inclined receptacle, the machine is set in motion. At what I will call the "home station," shells are both received into and discharged from the machine. These stations are the points where the shell-holders remain stationary during the interval between the intermittent motions of the disk D.

I will describe the passage of a shell through the machine and the different operations incident thereto. As a holder approaches the home station, the door of the holder is opened by the engagement of the pin d' at the bottom of the door with the incline a' . When the holder stops, it will be directly over an opening, a , in the table a , through which the cartridge, if there be one in the holder, will be discharged from the machine. During the next upward stroke of the cross-head the disk is again advanced, the holder in question still having its door held open by the incline aforesaid. Just as the holder is starting from the home station it passes under the guiding-tube O' . At this moment the door of the guiding-tube is closed, and a shell, by means of the cut-off device above, is discharged through it into the holder. At the next instant the door of the guiding-tube is opened, and the door of the holder is closed on the shell, holding it firm, and immediately after the station that I will name "2" is reached. The next downstroke punches the cap from the shell, the following up-stroke advances the shell to station 3, when the succeeding downstroke caps the shell. These two devices (the punch and capper) are only used when old shells are being filled. When new shells are used, these two devices are either removed from the machine or the punch P and set P' are screwed up so high as to be inoperative. At station 4 the shell receives the powder, and at station 5 a wad. At station 6 the shot is added, and at station 5 another wad is placed. At station 8 the crimping or creasing is done, and at station 9 the cartridges are marked. This completes the cartridge, and it is now ready to be discharged, which will be done at the next or home station already described.

In case it is desired to place more than one wad—as, for instance, over the powder—it may be accomplished by increasing the thickness of the wad-pusher l and the fingers attached and raising the thimble k , in which case more than one wad might be placed in the shell by one stroke of the rammer; also, it is practicable to make larger machines with more stations, holders, and other accompanying parts, so that duplicate devices for placing wads in the shells may be added between the powder and shot

container, or even after the shot-container, if desired.

I hereby reserve to myself the right to embody in a separate application for Letters-Patent the arrangement for creasing cartridge-shells herein described, and illustrated in Fig. 22 of the drawings.

What I claim is—

1. In a machine for filling cartridges, the combination, with a shell-feeder and an intermittently-rotating device carrying shell-holders, of a powder-container, a wad-feeder, and a shot-feeder, and means for automatically actuating the same, whereby the shells are fed and filled, substantially as set forth. 75
2. In a machine for filling cartridges, the combination, with the main structure thereof, and a cross-head arranged to reciprocate upon said structure, of a rotary crimper-rod carried upon said cross-head, and provided at its lower end with devices for automatically embracing the sides of the shell, substantially as and for the purposes set forth. 85
3. In a machine for filling cartridges, the combination, with the main structure thereof, of a reciprocating cross-head and a yielding marker adapted to be actuated thereby, and means for holding the shell during the operation of marking, substantially as shown and 95 described. 90
4. In a machine for filling cartridges, the combination of the main structure thereof with the reciprocating cross-head, a punch adapted to be actuated thereby, and a support for the shell, the said punch being adapted to enter the shell and force the prime therefrom, substantially as shown and described. 100
5. In a machine for filling cartridges, the combination, with the main structure thereof, an actuating cross-head or equivalent device, and means for operating the same, of the shell-feeder, the punch adapted to enter the shell and remove the prime, the prime-set adapted to enter the shell, the automatic prime-feed tube, the yielding seat to receive the shell, whereby the prime is fixed thereto, the automatically-discharging powder-container, the wad-feeder, the automatically-discharging shot-container, the crimper mechanism adapted to act upon the periphery of the shell to crimp the same, the wad-marking device, and devices for discharging the completed cartridge, the said several devices here named being arranged and adapted to be automatically operated in proper order, substantially 115 as shown and described. 105
6. In a machine for filling cartridges, the combination, with the main structure, a reciprocating cross-head or equivalent device mounted thereon, and the connections for actuating the same, of a rammer, adjustably connected to said cross-head, and arranged to adjust the pressure and maintain the uniformity of the same, substantially as set forth. 125 120
7. In a machine for filling cartridges, the combination, with the main structure thereof 130

and a reciprocating cross-head or equivalent device, of the adjustable rammer, provided with the slip-joint and springs, whereby any excess of pressure upon the parts may be relieved, substantially as and for the purpose set forth.

8. In a cartridge-filling machine, wad-holders the cases of which are provided with elastic parts adapted to expand or open sufficiently to receive wads, singly or in quantities, thrust in at the sides of the holder, substantially as and for the purpose shown and described.

9. In a cartridge-filling machine, wad-holders adapted to receive wads in quantities through the sides by means of the elasticity of the parts, and so constructed and arranged that the wads in the holder are always exposed to the view of the operator, substantially as described, and for the purpose specified.

10. In a cartridge-loading machine provided with wad-holders, adjustable passage-ways through which wads may be pushed from the holders in desired quantities, substantially as and for the purpose set forth.

11. In wad-holders for a cartridge-loading machine, provided with adjustable passage-ways, through which wads are pushed from the wad-holder, movable collars, gates, or equivalent devices adapted to adjust the said passage-way to a desired size, substantially as described, and for the purpose set forth.

12. In a cartridge-filling machine, the combination, with the wad-holders, and the wad-rammers, of the yielding fingers for holding the wads in position to be operated upon by the rammers, and the wad-pushing slide provided with an extension for operating beneath the wad-holders, substantially as described.

13. In a cartridge-filling machine, the combination, with the yielding wad-starting tube, of the wad-rammer, whereby the wad is accurately conveyed to and forced into the shell, substantially as described.

14. In a cartridge-filling machine, the combination of the wad-holder with the slide provided with an extension constituting a wad-pusher, and mechanism for operating the same, substantially as set forth.

15. In a cartridge-filling machine, the combination, with the wad-pushers, of the slotted levers connected therewith, the spindles to which said levers are attached, and the levers mounted upon said spindles and arranged to be engaged by the passing cartridge-shells contained in the holders, whereby the slotted levers are actuated to move the slides or pushers when the shells are in the holders contiguous to the respective levers, substantially as described, and for the purpose specified.

16. In a cartridge-filling machine provided with gates or valves for measuring and discharging powder and shot, the secondary chamber provided with elastic filling, substantially as shown and described.

17. In a machine for filling cartridges, the combination, with the shot or powder container and the means for automatically opening and closing the same, of the lever secured to the said container and adapted to be actuated by the shell to be filled, whereby the devices which open the cut-off valve in the container are made to engage each other and the valve opened, substantially as described.

18. In a machine for filling cartridges, the combination, with the main structure thereof, of the intermittently-rotating disk mounted upon a suitable column, and adapted to support the holders and to receive the said motion through the action of a rotating shaft provided with arms or levers which engage recesses or holes in the under side of the said disk, substantially as described.

19. In a machine for filling cartridges, the combination, with the intermittently-rotating disk provided with holes or notches on the under side thereof, of the rotating shaft provided with radial levers or arms, and the cam for actuating and stopping the said disk, substantially as shown and described.

20. In a machine for filling cartridges, the combination, with the main structure thereof, of the spider mounted upon the central column of the main structure, and provided with radial arms or levers arranged to support the powder and shot discharging devices, and the wad-pushers, substantially as shown and described.

21. In a machine for filling cartridges, the combination, with the main structure thereof, the hollow shaft, the bolt therein, and the nut connecting the two together, of the spider and the device for connecting the same with the bolt, substantially as shown and described.

22. In a machine for filling cartridges, the combination, with the cartridge-carrier provided with a cut-off arranged to receive, retain, and discharge the cartridges one at a time, of a cartridge-guiding tube arranged to receive the cartridges from the carrier and to deliver them to the cartridge-holders, substantially as shown and described.

23. In a machine for filling cartridges, the combination, with the cartridge-carrier provided with a cut-off and means for actuating the cut-off, of a cartridge-guiding tube adapted to receive them from the carrier and to deliver them to the holders, substantially as shown and described.

24. In a machine for filling cartridges, the combination of the inclined cartridge-carrier with the transverse rock-shaft, having arms extending therefrom and the cut-off device secured thereto, and means for automatically actuating the same, substantially as described.

25. In a machine for filling cartridges, the combination of the slotted actuating-rod, the rock-shaft, its extending arms, and the cut-off device secured thereto, with the two-part guiding-tube adapted to engage one of said arms, and the intermittently-rotating disk provided

- with shell-holders, the said devices being constructed and arranged so as to co-operate and properly conduct, discharge, and receive the shells, substantially as shown and described.
26. In a cartridge-filling machine, the combination, with the main structure and a reciprocating cross-head mounted thereon, of the crimper-rod provided with the spiral bead, the thimble E, situated above the bead, and a coiled spring depending from the thimble and arranged to engage said bead, substantially as set forth.
27. In a cartridge-filling machine, the combination, with the main structure and a reciprocating cross-head mounted thereon, of the crimper-spindle provided with a slip-joint, a spiral spring attached thereto, and jam-nuts arranged to bear upon said spring so as to adjust its tension, substantially as described.
28. In a cartridge-filling machine, the combination, with the main structure and a reciprocating cross-head mounted thereon, of a crimping device provided at one end with a recess of the proper configuration to crimp the cartridge-shell, and at its opposite ends with quick threads, which latter engage with similar threads in the cross-head, substantially as set forth.
29. In a cartridge-filling machine, the combination of the main supporting structure, a crimping device having a quick thread upon its spindle, a thimble, E, a worm-bead upon said spindle below the thimble, a spiral spring depending from the thimble and engaging said bead, and a reciprocating cross-head or equivalent device provided with quick threads adapted to register with the quick threads in the crimper-spindle, substantially as set forth.
30. In a cartridge-filling machine, the combination, with the table provided with the orifice α^6 and the incline α^4 , of the disk D, provided with the holders d, substantially as shown and described.
31. In a cartridge-filling machine, the combination, with the intermittently rotating disk, the cartridge-holders, and the crimping de-

vice, of the pivoted toothed lever and the fixed dog, whereby the shell is prevented from revolving during the operation of crimping, substantially as shown and described. 50

32. In a cartridge-filling machine, the combination, with the intermittently-rotating disk, devices for operating the same, and cartridge-holders attached to said disk, of the pivoted toothed lever and the fixed dog, said lever and dog being arranged to receive the cartridge-shell between them and to prevent said shell from revolving during the operation of crimping, substantially as shown and described. 55

33. In a cartridge-filling machine, the combination, with the main structure, of a rotating disk mounted upon said structure and provided with a series of recesses, a pivoted spring-actuated lever arranged to engage by its free end with said recesses, and devices for throwing said lever out of engagement with said recesses, for the purpose set forth. 60

34. In a machine for filling cartridges, the combination, with the main structure and a table mounted thereon and provided with an aperture, of a reciprocating cross-head and a punch attached thereto, arranged to enter the cartridge-shell and to force the priming therefrom through the aperture in the table, substantially as shown and described. 70

35. In a cartridge-filling machine, the table provided with a recess, an anvil located in said recess, a feeding device for conducting the primings to the anvil, and a yielding bearing for said feeder, in combination with the reciprocating primer-setting punch, arranged to enter the cartridge-shells and affix the primings thereto, substantially as shown and described. 75

In testimony whereof I have signed this specification in the presence of two subscribing witnesses.

FRANKLIN L. CHAMBERLIN.
